DESIGN FOR A TOOL POST FOR LATHES

Barney Long, Minneapolis, Minn.

Application March 22, 1939, Serial No. 83,747

Term of patent 14 years

To all whom it may concern:

Be it known that I, Barney Long, a citizen of the United States, residing at 4556 Oliver Ave. No., Minneapolis, in the county of Hennepin and State of Minnesota, have invented a new, original, and ornamental Design for a Tool Post for Lathes, of which the following is a specification, reference being had to the accompanying drawings, forming part thereof.

Fig. 1 is a top plan view of a tool post for lathes showing my new design;

Fig. 2 is a side elevational view thereof.

Fig. 3 is a front elevational view thereof.

Fig. 4 is a rear elevational view thereof.

I claim:

The ornamental design for a tool post for lathes, substantially as shown.

BARNEY LONG.
